UNITED STATES PATENT OFFICE.

TRUMAN S. CALDWELL, OF RACINE, WISCONSIN, ASSIGNOR TO RACINE HORSESHOE TIRE COMPANY, OF RACINE, WISCONSIN, A CORPORATION OF WISCONSIN.

DESIGN FOR A TIRE.

Application filed January 12, 1927. Serial No. 20,354. Term of patent 3½ years.

To all whom it may concern:

Be it known that I, TRUMAN S. CALDWELL, a citizen of the United States of America, residing at Racine, county of Racine, and State of Wisconsin, have invented a new, original, and ornamental Design for Tire, of which the following is a specification, reference being had to the accompanying drawing, forming a part thereof.

In the accompanying drawings:

Fig. 1 shows in plan a part of a tire embodying the design.

Fig. 2 is a side elevation of a part of the tire embodying the design.

Fig. 3 is a cross section on the line 3—3, Fig. 1.

I claim:

The ornamental design for a tire, substantially as shown.

TRUMAN S. CALDWELL.
